UNITED STATES PATENT OFFICE

2,439,124

CENTRIFUGAL FAN

Carl O. Bergstrom, Boston, Mass., assignor, by
mesne assignments, to Westinghouse Electric
Corporation, a corporation of Pennsylvania

Application September 26, 1944, Serial No. 555,780

1 Claim. (Cl. 230—259)

1

This invention relates to centrifugal fans and relates more particularly to centrifugal fans which may be supported from a ceiling and which may be used for drawing large volumes of air from above the ceiling and for discharging it into the space below the ceiling.

In passenger vehicles such as railway passenger cars, buses, and rapid transit cars, comfortable conditions may be maintained in summer by blowing large volumes of outdoor air through the space occupied by the passengers. This is known as pressure ventilation.

This invention provides a centrifugal fan particularly suitable for pressure ventilation of passenger vehicles. It is adapted to be attached to a ceiling around a circular aperture therein and discharges outdoor air drawn from above the ceiling outwardly as well as downwardly into the passenger space. Several such fans may be spaced along the longitudinal center of a passenger vehicle.

An object of the invention is to improve centrifugal fans used for pressure ventilation.

The invention will now be described with reference to the drawing, of which:

Fig. 1 is a plan view looking downwardly upon a fan embodying this invention;

Fig. 2 is a sectional view along the lines 2—2 of Fig. 1 except that the motor is not shown in section;

Fig. 3 is a plan view looking upwardly upon the fan of Figs. 1 and 2, with a portion of the back plate of the fan wheel removed, and

Fig. 4 is an enlarged sectional view along the lines 4—4 of Fig. 1.

The fan wheel is made up of the blades 5, the side plate 6 to which the front edges of the blades are attached as by welding, the backplate 7 to which the back edges of the blades are attached, and the hub 8 to which the backplate is attached by the rivets 9. The vertical shaft 10 of the electric motor 11 extends through the hub 8 and has a lower threaded portion upon which is screwed the nut 12 which retains the hub upon the shaft 10.

The ceiling 13 has an aperture 30 which is circular except for the inward extensions 23, for receiving the fan assembly which is supported within the aperture as best illustrated by Figs. 2 and 4.

The centrally apertured inlet plate 14 is attached as by the bolt 15 between the annular rings 16 and 17. The annular ring 18 is attached to the ring 17 by the bolt 19 and overlies the extensions 23 and is attached to the upper surface thereof by the screws 20.

2

The motor 11 is supported upon the ring 16 by the arms 21.

The inlet plate 14 has a curved lower portion which converges downwardly and extends within the central opening in the side plate 6.

The relatively long bolts 26 extend through the annular ring 18 and below same and support the deflector plates 22 which are formed as frustums of cones. The plates 22 have the air deflection faces 24 which may be formed at angles of 19° to the horizontal.

The upper plate 22 is spaced from the ring 18 by the relatively long, tubular spacer 25 which extends around the bolts 26 and which has its lower end angled to conform with the angled surface of the upper plate. The similar tubular spacers 27 extend around the bolts 26 between the plates 22; have their upper and lower surfaces angled to conform with the angled surfaces of the plates, and space the plates 22 the same distances apart.

The side plate 6 in its air delivery portion, and the backplate 7 are shaped so as to extend substantially parallel to the angled faces 24 of the deflector plates 22. The fan wheel thus turns and discharges the air moved thereby in streams which are in alignment with the deflection faces of the deflector plates with the result that there is a minimum of turbulence and noise.

In operation, the fan draws air from above the ceiling and forces it downwardly and outwardly into the passenger space. Experience has shown that when the air is blown directly downwardly into the passenger space, the effect is uncomfortable due to the large volumes it is necessary to handle. By blowing the air slightly downwardly as disclosed herein, it penetrates all portions of the passenger space and without discomfort.

While one embodiment of the invention has been described for the purpose of illustration, it should be understood that the invention is not limited to the exact apparatus and arrangement of apparatus illustrated as modifications thereof may be suggested by those skilled in the art without departure from the essence of the invention.

What is claimed is:

A pressure ventilating fan comprising a motor having a shaft extending vertically downward, a fan wheel on the lower end of said shaft, and a plurality of spaced deflectors formed as frustums of cones having axes coinciding with the axis of said shaft, supported around said wheel, said wheel having a side plate terminating adjacent the upper end of the uppermost of said de-

deflectors and extending parallel thereto, said wheel having a back plate terminating adjacent the upper end of the lowermost of said deflectors and extending parallel thereto, said back plate being imperforate whereby all of the air from said wheel is directed between said deflectors.
